MODULAR BLOCK

Richard A. Rose, 1545 Collins Ave.,
Miami Beach, Fla. 33139

Filed Apr. 11, 1966, Ser. No. 1,834

Term of patent 14 years

Int. Cl. D25—01

U.S. Cl. D13—1

FIGURE 1 is a perspective view of my modular block showing my new design;

FIGURE 2 is a plan view of my modular block;

FIGURE 3 is an end elevational view with respect to FIGURE 2 of my modular block; and

FIGURE 4 is a partial elevational cross-section of my modular block taken along line 4—4 of FIGURE 2.

I claim:

The ornamental design for a modular block, substantially as shown.
